Primary Examiner — Paula Greene(74) *Attorney, Agent, or Firm* — Winston Hsu; Scott Margo**CLAIM**

The ornamental design for a wearable electronic device, as shown and described.

DESCRIPTION

FIG. 1 is a front perspective view of a first embodiment of a wearable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the same wearable electronic device in an alternate position thereof;

FIG. 9 is a front perspective view of second embodiment of a wearable electronic device showing our new design;

FIG. 10 is a front view of the wearable electronic device in FIG. 9;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a front perspective view of the second embodiment of wearable electronic device in an alternate position thereof. The broken lines illustrating portions of the wearable electronic device from no part of the claim design.
